Des. 214,611
Patented July 1, 1969

214,611

MOTORCYCLE HANDLEBAR DEMONSTRATION UNIT

Frank G. Stone, Long Beach, Calif., assignor of one-half to Peter Mead, Canoga Park, Calif.

Filed Apr. 3, 1968, Ser. No. 11,281

Term of patent 14 years

Int. Cl. D12—14

U.S. Cl. D90—11

I claim:

The ornamental design for a motorcycle handlebar demonstration unit, substantially as shown and described.
